UNITED STATES PATENT OFFICE.

HIRAM T. MERRILL, OF CHICAGO, ILLINOIS.

PIANO-STOOL.

SPECIFICATION forming part of Letters Patent No. 324,143, dated August 11, 1885.

Application filed September 26, 1883. (No model.)

To all whom it may concern:

Be it known that I, HIRAM T. MERRILL, a citizen of the United States, residing in Chicago, county of Cook, and State of Illinois, have 5 invented certain new and useful Improvements in Piano-Stools, of which the following is a specification.

This invention relates to improvements in piano-stools provided with means for vertically adjusting the seat; and the objects of the invention are to prevent the seat from having a rocking movement upon its threaded bearing, to exclude dust from said bearing, to decrease the cost and increase the durability 15 of the stool by providing a standard having cast therewith screw-threads forming the bearing for the stool, to provide for a detachable connection of separate leg-supports with the standard, and to provide such a stool with a 20 cast-metal seat. These objects are attained by devices illustrated in the accompanying drawing, in which is shown a side elevation of a stool, partly in section, embodying the invention herein described and claimed.

25 A designates a circular seat, made entirely of cast metal and slightly concaved on its upper face, and provided with a downwardly-curving flange, *a*, after the usual form in which these seats have heretofore been constructed, 30 the central or main portion of the seat being cast with perforations or an open-work representing any tasty design—such as flowers, leaves, or fanciful figures—which will admit of a free circulation of air through the seat.

35 Cast with and on the under side of the seat are lugs or enlargements *b*, corresponding in number with the seat-supporting arms cast upon the sleeve *B*, said lugs *b* being provided with screw-threaded recesses forming seats for 40 set-screws *d*, which unite the seat with and clamp it firmly upon the arms *c*. By this construction the seat may be made to present a very light and artistic appearance and yet embody all the necessary strength, and at the 45 same time avoid the clumsy appearance so common to wooden and upholstered seats, and their liability to work loose on their fastenings, and to crack and split.

Other advantages accruing to a cast-metal 50 seat are its cheapness in cost, the facility with which they may be produced in large num-

bers, and the saving in time and labor required in finishing them for use after once being shaped.

Sleeve *B* is cast with internal threads, *e*, 55 which extend on either side of its center of length a sufficient distance to afford a substantial bearing for the male screw it receives, and to leave at each end smooth-bored and enlarged chambers *f g*, respectively; but it may 60 here be stated that chamber *f* may be omitted and the screw-thread extend up to the top of the sleeve, so far as the present invention is concerned. Working in this sleeve are screw-threads *h*, cast with and upon the standard or 65 post *C* of the stool, which standard has also cast therewith a shoulder or ring, *i*, which limits the downward adjustment of the sleeve and forms a solid base for the same when the stool is screwed down. 70

For a short distance below the screw-threads *h* the standard *C* is reduced in diameter, as shown at *j*, said reduced portion terminating abruptly in what may be termed a "shoulder," *k*, which is of a sufficient diameter to permit the chambered portion *g* of the sleeve to fit snugly over it, the length of the shoulder *k* being preferably sufficient to correspond with the ordinary adjustments of the stool, so that in such adjustments the chamber *g* will 75 80 embrace the shoulder and exclude dust and other foreign substances from the bearings of the stool, and besides prevent an otherwise unsightly break in the outline of the sleeve and standard and keep the stool from rocking. 85

Chamber *g* has another important function in that it prevents an accidental detachment, sometimes unpleasant to the operator, of the sleeve and seat from the standard when the 90 seat is screwed to a height sufficient to detach its screw-threads from the standard, for, as will be seen, in such case the chamber *g* will extend sufficiently down on the screw of the standard to maintain the sleeve thereon, no 95 matter to what extent the turning of the stool may be maintained.

The lower end of the standard is cast with a concave bearing, *l*, to receive corresponding lugs, *m*, projecting from each of three or more 100 scroll-legs, *D*, the angles of these lugs being formed on a radius, so as to fit close together,

and having their edges or apices truncated, so that by means of a bolt, *n*, dropped through the hollow standard and a nut, *o*, they may be clamped tightly but removably in their bearing. By forming upon the standard a globe-like enlargement the upper scroll portion of the legs may also have a bearing tending to steady and render them rigid; but usually this is more for ornamentation than other purposes.

Attaching the legs in the manner described enables them to be cast separately and in complicated designs, not possible if they were necessarily integral with each other, and besides such an attachment is not only simple but effective.

In conclusion, it should be stated that, so far as the cast-metal seat is concerned, it may be secured to arms upon an externally screw-threaded rod or tube working in a socket in the standard.

Having described the invention, what is

claimed and desired to be secured by Letters Patent is—

1. The combination, with the seat-supporting sleeve provided with a chamber, *g*, of the screw-threaded standard provided with a shoulder, *k*, adapted to work in said chamber, substantially as and for the purpose described. 25

2. The combination, with the standard provided with screw-threads, a shoulder, *k*, and ring *i* cast thereon, of a screw-threaded seat-supporting sleeve working on said standard and provided with a chamber, *g*, substantially as described. 30

3. The combination, with the standard provided with a hollow bearing, *l*, of the legs *D*, having lugs *m*, fitting in said bearing, and the bolt *n* and the set-screw *o*, substantially as described. 35

HIRAM T. MERRILL.
